CONTROL FOR AN ELECTRIC BLANKET

John R. Wilson, Royal Oak, Mich., assignor to Sunbeam Corporation, Chicago, Ill., a corporation of Illinois

Filed Dec. 27, 1967, Ser. No. 9,944

Term of patent 14 years

U.S. Cl. D26—13
Int. Cl. D13—03

FIG. 1 is a perspective view of a control for an electric blanket showing my new design;

FIG. 2 is a top plan view thereof;

FIG. 3 is a side elevational view, the opposite side being substantially a mirror image thereof;

FIG. 4 is a rear elevational view thereof; and,

FIG. 5 is a front elevational view thereof.

The bottom of the control for an electric blanket embodying my design is plain and unornamented. The dominant features reside in the solid line portions.

I claim:

The ornamental design for a control for an electric blanket, as shown and described.
